UNITED STATES PATENT OFFICE

JOSEPH I. GRISKO, OF CICERO, ILLINOIS

CAN PUNCH

Application filed October 19, 1931. Serial No. 569,689.

This invention relates to hand tools for opening cans, and more particularly to a tool for punching in the scored areas ordinarily provided on the tops of cans containing 5 scouring or cleaning powders. The scored areas are usually circular in outline and arranged in an annular series at the middle of the can top, and the scored areas are adapted to be broken or punched in to form the sifting 10 openings when the can is put in use.

The main object of this invention is to provide a tool by the use of which a series of sifting openings can readily be punched in a can top, particularly where the scored areas have 15 been provided in the standard manner above referred to.

Another and important object of the invention is to provide a tool which will permit some or all of the sifting openings to be 20 opened simultaneously and which provides for progressive engagement of the can top by the tool so that less resistance to perforation of the can top will be encountered.

A preferred embodiment of the invention 25 is illustrated in the accompanying drawing, where:

Figure 1 is a perspective view of a tool embodying the invention as positioned when 30 about to be used to perforate a can top;

Figure 2 is a sectional view on the line 2—2 of Figure 1, showing certain of the prongs as 35 partially through the can top;

Figure 3 is a side elevation of the tool, showing the alternative arrangement of long 40 and short prongs; and

Figure 4 is a plan view of the tool from the side opposite that on which the prongs extend.

The tool preferably comprises a flat handle 45 10, on one end of which there is formed a head 11, which is preferably of the flat circular or annular shape illustrated. From one face of this head there extends a series of 45 conical prongs 12 and 13. In the present instance these prongs are shown as alternately long 12 and short 13 for a purpose to be described, and also as having rounded or blunt ends better adapted for pushing the scored 50 areas of the can top inwardly in the specific application of the invention herein disclosed.

The prongs are preferably disposed in an annular series adjacent the peripheral edge of the head of the tool, which is also preferably circular, and the prongs are equally spaced a distance corresponding with the 55 spacings of the scored areas on standard can tops. In the present instance the head is illustrated as an annulus or ring having one edge 14 extending on the chord of the opening in the head and adapted to constitute, in combination with the head, a standard form of bottle cap remover.

By forming the prongs alternately long and short, as herein specifically disclosed, or by forming one or more of the prongs longer 65 than the others it is made possible to perforate or open certain of the scored areas only where it is not desired to open the entire series. Moreover, when the entire series of scored areas are to be opened, the provision of 70 long and short prongs reduces the force necessary to be applied as prongs will progressively engage the can top, the longer ones going through first and then the shorter ones.

It will accordingly be seen that a tool has 75 been provided which will quickly and easily produce the sifting openings in can tops as may be desired, instead of employing a single prong implement such as a pencil or ice pick, as has heretofore been the custom, and 80 it will be obvious that the embodiment of the invention here disclosed in one specific form may be considerably varied without departure from the scope of the invention, as we find in the form of the claims. 85

What is claimed is:

1. A can punch comprising a handle, a flat circular head on one end thereof, and an annularly disposed series of tapered prongs extending from one face of the head adjacent 90 the periphery thereof, certain of said prongs at diametrically opposite points on said head extending beyond other intermediate prongs.

2. A can punch comprising a handle, a flat circular head on one end thereof, and an annularly disposed series of tapered prongs extending from one face of the head adjacent 95 the periphery thereof, the prongs forming the series being alternately long and short.

3. A tool for punching in the series of 100

scored areas on standard cleaner can tops, comprising a flat head having a handle extending from one edge thereof, and a series of spaced prongs projecting from one side of the head in position to register with the scored areas on such can tops, one or more of said prongs being longer than the other prongs in the series.

In testimony whereof I affix my signature.

JOSEPH I. GRISKO.
